UNITED STATES PATENT OFFICE.

EDWARD A. LANGENBACH, OF CANTON, OHIO.

DESIGN FOR A METAL FINISHING-PLATE.

SPECIFICATION forming part of Design No. 23,283, dated May 22, 1894.

Application filed April 23, 1894. Serial No. 508,740. Term of patent 7 years.

To all whom it may concern:

Be it known that I, EDWARD A. LANGENBACH, a citizen of the United States, and a resident of Canton, county of Stark, State of Ohio, have invented and produced a new Design for Finishing-Plates, of which the following is a full, clear, and exact description, reference being had to the accompanying drawing, making part of this specification.

- 10 The accompanying drawing is a plan view of the design.
My design consists of a square or rectangular metallic finishing plate A, divided into sub-divisions by series of short broken or intersected oval ribs, or upwardly projected portions *a* and *b*, extending across the plate on lines at right angles to each other, and rosettes or circular projections *c*, situated at a point where the ribs *a* and *b* would cross 15 if continued, and the open space between the ends of the ribs and the rosettes. Within the square formed or outlined by the ribs *a* and *b*, are interlacing rings *f*, *g*, *h*, *i*, having within the circles described thereby, a raised 20 circular portion *j*, a circular rib *k*, a distance 25 from the raised portion *j*, and connected

therewith by the ribs *l*, and the radial ribs *m*, projected palmately from the rib *k*, and increased in breadth, and circular at their end portions. The corners or angles formed by the ribs *a* and *b*, are adorned by a figure having a lobed body or central portion *n*, and outwardly projected members *o*.

The essential feature of my design is a metallic finishing plate divided into sub-divisions by series of sectional or intercepted ribs at right angles, the circular projections *c*, the open space between the ends of the ribs and the raised circular portions. The interlacing rings, the palmate and the corner ornament, having a raised lobed body, and decreasing projected members.

What I claim is—

The design for metallic finishing plates herein shown and described. 45

In testimony whereof I have hereunto set my hand this 14th day of April, A.D. 1894.

EDWARD A. LANGENBACH.
